UNITED STATES PATENT OFFICE.

RUDOLPH WINCHEL, OF WEBB CITY, MISSOURI.

GROCER'S BIN.

No. 806,719.

Specification of Letters Patent.

Patented Dec. 5, 1905.

Application filed April 22, 1905. Serial No. 256,969.

To all whom it may concern:

Be it known that I, RUDOLPH WINCHEL, a citizen of the United States, residing at Webb City, in the county of Jasper and State of Missouri, have invented new and useful Improvements in Grocers' Bins, of which the following is a specification.

My invention has relation to improvements more particularly in grocers' bins, &c.

10 Objects of the invention are to provide for conveniently filling and emptying the bins, to suitably display the goods and to permit the removing of the same from the bins to advantage, and to secure the aforesaid objects in a 15 simple, inexpensive, and effective manner.

Said invention consists of certain structural features, substantially as hereinafter fully disclosed and particularly specified.

In the accompanying drawings, illustrating 20 the preferred embodiment of my invention, Figure 1 is a perspective view thereof with the bin member or apartment proper tilted into its open position and the lid or cover of the lower scoop-bin compartment extended 25 and serving as a counter. Fig. 2 is a vertical longitudinal section of the bin member or apartment detached from the supporting frame or entablature. Fig. 3 is a transverse section thereof mounted in operative position 30 in said frame produced through an upper and a lower bin-compartment looking toward the end wall and showing the pivotal or rockable connection therebetween. Fig. 4 is a horizontal section of the same, taken through an upper 35 bin-compartment viewing downward, disclosing more especially in plan the sectional bottom for delivering or removing the bin contents into the scoop-bin compartment below. Fig. 5 is a detail perspective view of one of 40 the supplemental pieces or partitions.

In the disclosure of my invention I provide a bin apartment, receptacle, or member 1 and an upright frame or entablature 2, within which the former is pivotally supported or mounted, 45 as later explained, and which is adapted to be suitably arranged in practice in the store-room, as will be readily understood. Said apartment, receptacle, or member 1 is preferably of the construction shown, having a number of upright compartments or upper bins 1^a arranged side by side, of any desired number and capacity, and communicating at their lower ends with a corresponding number of lower or what may be termed "scoop" bins or compartments 50 1^b. The upper ends or edges of the walls of said upper bins or compartment are inclined or

sloped rearward to permit the same to escape contact with the frame or entablature when tilted forward, and in the lower ends of these bins are correspondingly - sloped bottoms. 60 Each of said bottoms comprises a fixed member or section 1^{aa} and a movable or sliding section or member 1^{ab}, arranged to slide or move in under the fixed section, as in providing for delivering or removing the contents thereof 65 into the bins below, suitable cleats or pieces 1^{ac} being secured in position at the required inclination or angle for the support of said movable bottom section for that purpose. Said sliding or movable section is provided or 70 equipped with a thumb or finger piece or knob 1^{ad} for its convenient manipulation or movement, as occasion may require.

The bins 1^a are suitably fitted with glass or transparent fronts 1^e, and in rear thereof are 75 arranged at suitable intervals therefrom supplemental pieces or partitions 1^f to provide subchambers or compartments in said bins to be filled with a sample of the goods or article contained within the bin-chamber proper 80 and whereby the extent of the contents of the latter may be simulated, giving the same the appearance of being always full. Said partitions 1^f are provided with lateral edgewise-arranged pieces or cleats 1^g presented toward the 85 fronts of the bin chambers or compartments and serving to space off said partitions therefrom, and extending in a preferably downward and rearward inclination from said lateral cleats are opposite elongated slotted arms 90 or lugs 1^h, receiving the shanks of set or holding screws 1ⁱ, working or screwing into the sides of said bin-chambers. By this arrangement it is obvious that said partitions are held or clamped effectively in position and 95 that they may be removed and replaced as circumstances require.

The lower scoop bins or compartments 1^b, having their common forward bottom extension 1^k inclined upward and outward, themselves extend or project forward a suitable distance relatively beyond the front surface of the upper bin-compartments, thus providing for ready access to and the scooping out of the contents of said lower bin-compartments, as is apparent. Said lower bin-compartments have their partitions and the forwardly-extending portions of the sides of the receptacle or apartment, forming the end walls of the end bin-compartments, inclined 105 outward and downward to the oppositely-inclined forward bottom extension 1^k to render 110

said lower bin-compartments quite shallow at this point, the purpose of which is obvious. Secured to the forward edge of said bottom extension is an upstanding or vertical strip or 5 bar 1^a, and to this latter is suitably hinged or pivoted, as presently explained, the closure or cover 3 for the lower or scoop bin compartments 1^b, the same having a suitable handle 3^a and fitting down upon the forward extension 10 of the latter with its front and rear edges abutting the strip 1^a and the front surface of the upper bin-compartment as shown, making an effective closure therefor. Said cover or closure has its hinging or pivoting action 15 formed by applying thereto about centrally of its transverse area upon its inner surface preferably butt-hinges 4, one leaf of each of which is secured to the latter, and to the other leaves thereof are riveted preferably twisted 20 metal straps 4^a, with their inner ends pivoted or jointed to the outer ends of plates or bars 4^b. These in turn are pivoted to the inner surfaces of the end lower compartments or bins 1^b, whereby as said closure or cover is 25 extended or removed from said bins it is caused to assume a practically horizontal position for forming a support or counter upon which to temporarily rest sacks or bags containing the goods or articles it may be desired 30 to pour into the upper bin-compartments, as in filling or replenishing the same.

At the upper end of the receptacle or member 1 and upon the inner surfaces of the upper end compartments or bins thereof are applied pieces or stops 5, being removably held in place by nut-equipped screws 5^a passed therethrough and said receptacle at the lower rear edge thereof. These stops being effective to engage the supporting-frame 2 at the 35 inner side of its forward top portion serve to limit the forward tilting movement of the receptacle or member for exposing the upper ends of the upper bin-compartments, as in permitting ready access thereto for filling or 40 replenishing its contents.

At the upper forward end of the receptacle or member 1 is suitable means, as a catch 6, of the character shown or otherwise for the proper retention of said receptacle as against 45 movement or tilting forward when this is not required.

The receptacle or member 1 has suitably affixed to its bottom or under side within the plane principally of its upper bins or compartments, as well as its lower bins or compartments, notched or recessed castings 7, effective to engage or receive bearings or pivots 8, secured to the lower longitudinal or axial bar 2^x of the frame 2 to permit said 50 receptacle to have a forward tilting movement and of course when thus moved to allow of its being returned to its former position.

Also it is noted that by means of the aforesaid arrangement of the bins or compartments of the receptacle 1 the contents thereof, which are removed from below and which were supplied to said bins by the inverting of the sacks originally containing the same over said bins, may thus be dealt out from said bins to the best advantage, as is apparent. It is further called to attention that the frame member or entablature especially having its constituent parts put together by screws or like fastenings the same may be readily taken apart or "knocked down," as may be of convenience 75 for shipping, &c.

I claim—

1. A contrivance of the character described, comprising a bin member or receptacle, having a front sample-compartment embracing a partition having lateral edge right-angled portions equipped with downward and rearward inclined arms having longitudinal slots provided with downward-facing entrance-openings, and set or holding screws working 85 in said slots and the sides of said bin-member receptacle.

2. A contrivance of the character described, comprising a tilting receptacle provided with upper and lower compartments, the bottoms 90 of the upper compartments having adjustable or movable sections to establish communication between the lower compartments and the upper compartments, said lower compartments having forward extensions provided 95 with bottoms inclined outward and upward, and with a cover or lid effective to serve as a counter extension therefor.

3. A contrivance of the character described, comprising a compartment-receptacle provided with upper and lower compartments or bins, the upper compartments or bins having their bottoms provided with movable or sliding sections to establish communication between the upper and lower compartments 105 or bins, the lower compartments having forward-extending portions, equipped with a cover or closure effective in its extended position for use as a temporary support or counter.

4. A contrivance of the character described, comprising a compartment-receptacle having its lower compartments or bins extended forward, and a cover or closure for the forward extension of said bins or compartments, said 110 cover or closure being equipped with butt-hinges the inner leaves of which have fixed thereto plates pivoted to additional plates or members in turn pivoted to said receptacle.

In testimony whereof I affix my signature in presence of two subscribing witnesses.

RUDOLPH WINCHEL.
